ATTORNEY

UNITED STATES PATENT OFFICE.

WILLIAM SPARKS, OF JACKSON, MICHIGAN, ASSIGNOR TO THE SPARKS-WITHINGTON COMPANY, OF CLEVELAND, OHIO, A CORPORATION OF OHIO.

FAN.

1,256,941.

Specification of Letters Patent. Patented Feb. 19, 1918.

Application filed September 27, 1916. Serial No. 122,384.

To all whom it may concern:

Be it known that I, WILLIAM SPARKS, a citizen of the United States of America, and resident of Jackson, in the county of Jackson, in the State of Michigan, have invented new and useful Improvements in Fans, of which the following, taken in connection with the accompanying drawings, is a full, clear, and exact description.

10 This invention relates to certain improvements in fans and more particularly to pulley-driven radiator fans in which the entire structure constitutes a unitary article of manufacture and sale.

15 The object of the invention is to increase the efficiency of such apparatus in its adaptation to various uses, such as the cooling of automobile or other engines either directly or by water circulation through radiators 20 or the like and at the same time to produce a unitary structure made compactly and preferably of comparatively thin sheet metal and assembled in such a manner as to be at once light, strong, durable and capable 25 of being manufactured at a reasonable cost.

Other objects and advantages relate to the specific details of construction as will more fully appear from the following description taken in connection with the accompanying drawings in which:

Figure 1 is a plan view of the fan.

Fig. 2 is a view of the same taken at right angles to Fig. 1.

Fig. 3 is a section on line 3—3, Fig. 1.

35 Fig. 4 is a section on line 4—4, Fig. 1.

Fig. 5 is a section on line 5—5, Fig. 4.

Fig. 6 is a plan view of a portion of the blank from which the blade is formed.

40 The invention, as shown, embodies a unitary structure adapted to be mounted in any suitable manner as the one provided without the addition or assembly of other elements and comprises a web —1— formed with a series of radiating arms —2— and a centrally axially extending flange —3—. Each of the radiating arms —2— is adapted 45 to carry a thin blade —4— suitable connection being made in any desirable manner as by rivets —4'—. The blades —4— are integrally united at their inner ends by a continuous web secured to and lying in contact with the web —1—. The fan blades and the radiating arms are twisted or deflected so as to lie at an angle to the plane

of rotation of the fan for the usual purpose.

Each of the fan blades is provided with a flange —5— projecting radially from the end of the blade and extending somewhat laterally from its connection with the blade. 60 These flanges —5— are bent about the end portion of the blade so as to lie at substantially right angles to the longitudinal plane of the blade and are secured to the inner side of a circular rim —6— constituting 65 a connection for the ends of all the blades.

The rim —6— may be formed of a circular strip of thin sheet metal of any suitable width, as shown, of a width somewhat less than the lateral extension of the deflected blades so as to cover only a portion of the same and the flanges —5— are so formed as to extend circumferentially of the rim —6— in a plane distinct from the plane of the deflected blades and preferably 75 the rim has its opposite circumferential edges inturned somewhat constituting a channel strip, or rim, and the flanges —5— are of a width adapted to fit between the inturned edges and extend circumferentially 80 of the rim so as to constitute, when secured by rivets or otherwise, a rigid, strong connection between each of the blades and the rim.

The integral connection of the flanges 85 —5— to blades —4— preferably lies nearer one edge of the blade than the other so that when the flange is secured to the rim —6—, one edge of the blade, as the edge —7—, will not project materially beyond the adjacent edge of the rim —6— while the edge —8— of the blade will project some distance to the opposite side of the rim. This construction is further accomplished by rendering the blades somewhat concave so that the 95 edge —7— is curved inwardly somewhat beneath the adjacent edge of the rim while the edge —8— by reason of the concavity is turned outwardly from the opposite edge of the rim. This construction is particularly 100 advantageous for use in such association as automobile radiators and the like by reason of the fact that the rim will prevent the blades from coming in contact with the radiator should the fan become loosened with 105 respect to its supporting means.

The flange —3— formed upon the web —1— is of a diameter adapted to receive a

2

hollow cup-shaped hub —9— formed preferably of thin sheet metal and having its closed end projecting somewhat to one side of the web —1— but lying in a plane approximately coinciding with the plane of the adjacent edge of the rim —6—, and the flange —3— may be secured to the cup-shaped hub in any suitable manner as by rivets —10—.

10 The open end of the hub —9— is preferably provided with a radially and outwardly projecting flange —11— and a relatively small internal shoulder —12— adjacent the radially outwardly extending flange. Suitable bearings —13— and —14— are fitted within the hub —9—, and these may be any suitable roller, ball or other bearings, as desired. The bearing —13— being positioned within the hub —9— at a point adjacent radiation of the web —1— and the bearing —14— at a point adjacent the radiation of the flange —11— and preferably a washer —15— is fitted against the shoulder —12— to hold the bearing —14— in proper position. The shaft —16— is mounted in the bearings —13— and —14— and projects some distance from the bearing —14— for receiving any suitable supporting member, such as that indicated at —17—.

20 30 which member may be retained upon the shaft in any suitable manner as by nut —18—.

A pair of sheet metal ring-shaped pulley sections —19— and —20— are mounted upon the hub —9—, the section —19— being provided with an axially extending intermediate flange —22— resting upon the outer face of the flange —11— and a radially and inwardly extending portion —23— lying in contact with the inner face of the flange —11—. The section —20— is provided with an intermediate bead —24— resting upon the edge of the flange portion —22— of section —19— and a radially inwardly extending portion —25— lying in contact with the portion —23— of section —19—.

A suitable cap plate —26— is then fitted over the end of the shaft —16— to lie in contact with the outer face of the flange —11— and the sections —19— and —20—. The flange —11— and cap bolt —26— are rigidly secured together in any suitable way, as by bolts —27—. Preferably the portion 55 of the pulley sections —19— and —20— extending outwardly from the intermediate flange —22— diverge somewhat to facilitate the application and use of belt means. It will be readily understood that the entire 60 structure, including the pulley, rotates freely about the shaft —16— through the medium of bearings —13— and —14—.

Although I have shown and described one specific construction, combination and form 65 of elements as perhaps preferable, I do not

desire to limit myself to the details of any of the same as various changes may be made without departing from the spirit of this invention as set forth in the appended claims.

70

What I claim is:

1. In a fan, the combination with a web having a series of radiating arms of a second web having a series of radiating blades, means for securing the arms to the blades with the webs in substantial contact, a laterally extending flange on one web and extending through the other web, a hollow substantially cylindrical hub telescoped within said flange, an antifriction bearing within said hub, and a shaft mounted in said bearing.

75

2. In a fan, the combination with a web having a series of radiating arms of a second web having a series of radiating blades, means for securing the arms to the blades with the webs in substantial contact, a laterally extending tubular flange on one web, a hollow substantially cylindrical hub telescoped within said flange and secured thereto, and a shaft mounted within the hub.

80

3. In a fan the combination with a web having a series of radiating arms of a second web having a series of radiating blades and means for securing the arms to the blades with the webs in substantial contact and a cup-shaped hub extending through the webs.

85

4. In a fan the combination with a web having a series of radiating arms of a second web having a series of radiating blades, means for securing the arms to the blades with the webs in substantial contact and an axially extending cylindrical flange on one web and extending through the other web and a hollow cup-shaped hub telescoped within said flange.

90

5. In a fan the combination with a web having a series of radiating arms of a second web having a series of radiating blades and means for securing the arms to the blades with the webs in substantial contact, a cup-shaped hub upon which said webs are mounted and a radially and outwardly extending flange upon said hub and a pulley seated on and secured to said flange.

95

6. In a fan the combination with a web having a series of radiating arms of a second web having a series of radiating blades, means for securing the arms to the blades with the webs in substantial contact and an axially extending circular flange on one web and extending through the other web, a hollow cup-shaped hub upon which said circular flange is mounted, and a radially and outwardly extending flange upon said hub and a pulley seated on and secured to said flange.

100

7. In a fan the combination with a web having a series of radiating arms of a sec-

105

- ond web having a series of radiating blades and means for securing the arms to the blades with the webs in substantial contact, a cup-shaped hub upon which said webs are 5 mounted, a radially and outwardly extending flange upon said hub and a pulley seated on and secured to said flange, a pair of spaced anti-friction bearings within the hub and a shaft mounted in said bearings.
8. In a fan the combination with a web having a series of radiating arms of a second web having a series of radiating blades, means for securing the arms to the blades with the webs in substantial contact, an axially extending circular flange on one web and extending through the other web, a hollow cup-shaped hub upon which said circular flange is mounted, a radially and outwardly extending flange upon said hub and 15 a pulley seated on and secured to said flange, a pair of spaced anti-friction bearings within the hub and a shaft mounted in said bearings.
9. In a fan the combination with a web having a series of radiating arms of a second web having a series of radiating blades and means for securing the arms to the blades with the webs in substantial contact, a cup-shaped hub upon which said webs are 20 mounted, a radially and outwardly extending flange upon said hub and a pulley seated on and secured to said flange, a pair of spaced anti-friction bearings within the hub and a shaft mounted in said bearings.
- 25 10. In a fan the combination with a web having a series of radiating arms of a second web having a series of radiating blades, means for securing the arms to the blades with the webs in substantial contact, a cup-shaped hub upon which said webs are 30 mounted, a radially and outwardly extending flange upon said hub and a pulley seated on and secured to said flange, a pair of spaced anti-friction bearings within the hub, one positioned adjacent the radiation of 35 said webs and the other adjacent the radiation of said flange upon the hub and a shaft mounted in said bearings.
- 35 11. In a fan the combination with a web having a series of radiating arms of a second web having a series of radiating blades, means for securing the arms to the blades with the webs in substantial contact, an axially extending circular flange on one web and extending through the other web, a hollow cup-shaped hub upon which said circular flange is mounted, a radially and 40 outwardly extending flange upon said hub and a pulley seated on and secured to said flange, a pair of spaced anti-friction bearings within the hub, one positioned adjacent the radiation of said webs and the other adjacent the radiation of said flange upon the hub and a shaft mounted in said bearings.
- 45 12. In a fan the combination with a hollow hub of fan blades radiating from said hub, a radially and outwardly extending flange formed upon the hub, an annular pulley section having an intermediate flange conforming to the circumference of said radial flange upon the hub, a second annular pulley section and means for rigidly securing the pulley sections to said radial flange.
- 50 13. In a fan the combination with a hollow hub of fan blades radiating from said hub, a radially and outwardly extending flange formed upon the hub, an annular pulley section having an intermediate flange conforming to the circumference of said radial flange upon the hub, a second annular pulley section, an annular cap plate across the end of the hub and means for connecting the pulley sections, the radial flange and the cap plate.
- 55 14. In a fan the combination with a web having a series of radiating arms of blades secured to the arms, a circular rim, the blades being deflected out of alignment with the plane of rotation of the rim and flanges on the blades lying in the plane of rotation of the rim when the blades are deflected and means for securing the flanges to the rim.
- 60 15. In a fan the combination with a web of a series of radiating blades carried by the web, a circular rim, the blades being deflected out of alignment with the plane of rotation of the rim and flanges on the blades lying in the plane of rotation of the rim when the blades are deflected and means for 65 securing the flanges to the rim.
- 65 16. In a fan the combination with a web of a series of radiating blades carried by the web, a circular rim having its edges inturned to form a channel, the blades being deflected out of alignment with the plane of rotation of the rim flanges on the blades lying in the plane of rotation of the rim when the blades are deflected and positioned between the in-turned edges of the rim and means for 70 securing the flanges to the rim.
- 70 17. In a fan the combination with a series of blades of a web uniting the inner ends of the blades, a hollow cup-shaped hub secured to and within the web, the closed end of the 75 hollow hub projecting to one side of the web.
- 75 18. In a fan the combination with a series of blades of a web uniting the inner ends of the blades, a hollow cup-shaped hub secured to and within the web, the closed end of the hollow hub projecting to one side of the web, the open end of the hub provided with a radially and outwardly extending flange positioned upon opposite sides of the web, a pulley secured to and mounted upon said flange, bearings within said hub and a shaft 80 mounted in said bearings.
- 80 19. In a fan, the combination with a web having a series of radiating arms of a sec-

ond web having a series of radiating blades, means for securing the arms to the blades with the webs in substantial contact, a laterally extending flange on one web and extending through the other web, a hollow substantially cylindrical hub telescoped within said flange, an antifriction bearing within said hub, a shaft mounted in said bearing, and a rim connecting the outer ends of the blades.

20. In a fan, the combination with a web having a series of radiating arms of a blade secured to each arm, a cylindrical hub upon which the web is mounted, a pulley in connection with said hub, an antifriction bearing within the hub in substantial alinement with the web, a second antifriction bearing within the hub in substantial alinement with the pulley, and a shaft journaled in said antifriction bearings.

21. In a fan, the combination with a web having a series of radiating arms of a blade secured to each arm, a cylindrical hub upon which the web is mounted, a pulley in connection with said hub, a plurality of spaced antifriction bearings within the hub, and a rim connecting the outer ends of the blades.

22. In a fan, the combination with a series of blades of a web uniting the inner ends of the blades, a hollow cup-shaped hub extending through the web, the closed end of the hollow hub projecting to one side of the web, an antifriction bearing within the hub in substantial alinement with the web, and a shaft mounted in said bearing.

23. In a fan, the combination with a series of blades of a web uniting the inner ends of the blades, a hollow cup-shaped hub

extending through the web, the closed end of the hollow hub projecting to one side of the web, an antifriction bearing within the hub in substantial alinement with the web, a shaft mounted in said bearing, and a pulley in connection with said hub.

24. In a fan, the combination with a web having a series of radiating arms, of a second web having a series of radiating blades, means for securing the arms to the blades with the webs in substantial contact, a laterally extending tubular flange on one web, a hollow substantially cylindrical hub telescoped within said flange and secured thereto, a flange formed upon the hub, and a pulley in connection with the flange.

25. In a fan, the combination with a series of blades, of a web uniting the inner ends of the blades, a hollow hub secured to and within the web, a pulley in connection with said hub, a shaft, anti-friction bearings mounted on the shaft and positioned within the hub, one of said bearings located adjacent the radiations of the blades and the other anti-friction bearing located adjacent the pulley, the bearing located against the radiations of the blades being unconnected to the hub and free to move axially therein with the shaft, and means for preventing the movement of the other anti-friction bearing axially of the hub.

In witness whereof I have hereunto set my hand this 23rd day of Sept., 1916.

WILLIAM SPARKS.

Witnesses:
